RAILWAY TRAFFIC CONTROLLING
APPARATUSLloyd V. Lewis, Pittsburgh, Pa., assignor to The
Union Switch & Signal Company, Swissvale,
Pa., a corporation of Pennsylvania

Application December 6, 1941, Serial No. 421,865

27 Claims. (Cl. 246—134)

My invention relates to railway traffic controlling apparatus, and more particularly, to an interlocking control system for governing the movement of traffic through a track layout comprising a plurality of track sections interconnected by track switches which may be variously arranged to form different traffic routes.

The system of my invention is of the entrance-exit route interlocking type in which the switches and signals for the different traffic routes are governed by the operation of push buttons mounted on a suitable control panel which also includes an illuminated diagram of the track layout. A push button is provided for each route end in the track layout, and the track switches are operated as required to establish a desired route in response to the successive momentary operation of the two push buttons identified with the opposite ends of the route, the signal at the entrance end clearing automatically as soon as the route becomes established.

My invention is an improvement upon that disclosed in my prior application for Letters Patent of the United States, Serial No. 252,803, filed January 25, 1939, for Railway traffic controlling apparatus, and also upon that disclosed in an application for Letters Patent of the United States, Serial No. 310,798, filed December 23, 1939, by Henry S. Young, for Railway traffic controlling apparatus.

One object of my invention is the provision of an improved arrangement of route selecting circuits requiring fewer route relays and a smaller number of contacts per relay than have been required heretofore in systems of corresponding scope.

A feature of my invention is the provision of improved and relatively simple arrangements for selection between alternative routes having the same route ends, and for the provision of through routing in the case of routes involving intermediate signals.

Another object of my invention is the provision of an improved control panel in which the route buttons and miniature levers for operating the track switches individually may be mounted in a row below the track diagram to secure a more compact arrangement, and in an improved arrangement for lighting the lamps of the track diagram. Other objects and features of my invention will be pointed out as the description proceeds.

I shall describe one form of my invention and shall then point out the novel features thereof in claims.

Referring to the accompanying drawings, Figs. 1A, 1B and 1C taken together show the track plan for a typical layout chosen to illustrate the route interlocking system of my invention, together with the circuits for the entrance relays and route relays associated with the operator's control panel and controlled directly by the operator in establishing the various routes. Fig. 2 shows the circuits for signal control relays for controlling the signals. Fig. 3 shows the usual section locking relays for providing sectional release of the switch locking. Figs. 4 and 5 show two types of circuits for the approach locking stick relays and those relays associated directly therewith. Fig. 6 shows the circuits for the switch locking relays and also for the switch control relays and the switch operating and indicating apparatus controlled thereby. Fig. 7 shows the circuits for the signal mechanisms. Fig. 8 shows circuits for section indication relays for controlling the route lamps on the operator's track diagram. Fig. 9 shows the circuits for the signal indication lamps on the track diagram. Fig. 10 shows the operator's control panel including an illuminated track diagram corresponding to the track layout and indicates the preferred location of the route buttons for controlling the circuits of Figs. 1A to 1C and of miniature switch levers L for operating the track switches individually. Fig. 11 shows the circuits for the indication lamps in the tracks of the diagram of Fig. 10.

Referring to Figs. 1A, 1B and 1C, the track layout shown is similar to that of my prior application hereinbefore referred to, and comprises the two main tracks of a double track railroad connected by three crossovers comprising the pairs of track switches 1A and 1B, 5A and 5B, and 7A and 7B, respectively, the lower track being also connected to a siding by single switch 3. All of the track switches are in their normal positions as shown. Train movements over the various traffic routes through the layout are governed by the signals 2, 4, 6, 8, 10 and 12, which signals are normally at stop, as shown. Signals 4 and 10 are two-arm signals each having a main arm such as 4A or 10A for governing high speed train movements over the main track in the normal direction, providing the track portion extending to the next signal in advance for the same direction, such as signal 23 or 20, is unoccupied, and also having a slow speed arm such as 4C or 10C which governs train movements over diverging routes and in addition serves as a 55 "call on" signal which may be cleared to admit

a train to an occupied main line route. Signals 2, 6, 8 and 12 are slow speed signals which may be cleared provided a proper route is set up but regardless of its occupancy. Signals 21 and 22 are distant signals for signals 4A and 10A, respectively. Signals 20 to 23, inclusive, are automatic block signals of the usual type and their control circuits have consequently not been shown herein.

The track rails are divided into track sections by the usual insulated joints, the upper track including the detector sections 1A and 5A, the approach sections 22T and 24T and the advance section 10T. The lower track includes the detector sections 4T, 3T and 7T, the approach sections 19T and 21T and the advance section 4T. Each track section is provided with the usual track circuit having a track battery as shown, at one end and a track relay TR at the other end, connected across the track rails. Each detector section track relay controls a slow pick-up slow release repeating relay TP, while each pair of approach section track relays controls an approach relay, such as relay 4AR or 10AR.

It will be noted that each relay shown herein is identified by a letter or combination of letters prefixed by the designation of the switch or signal with which the relay is associated, and that the circuits are arranged in the written circuit form with similar circuits grouped together in the same view. The contacts are identified by number, and above each contact may be found the designation of the relay which operates it. The terminals of the usual local source of current for energizing the relays are designated B and C, referring to the positive or supply terminal and to the negative or common return terminal, respectively.

Each track switch of Figs. 1A to 1C is arranged to be actuated by a power operated switch machine SM, which may be of the electric motor type, as in the system of my prior application, but preferably, and as shown herein, is of the electropneumatic type, such as is illustrated in the Coleman Patents Nos. 1,238,888 and 1,238,889, issued September 4, 1917, for Railway traffic controlling apparatus. The normal and reverse control magnets and the lock magnets for the switch machines 1A-SM and 1B-SM are shown herein in Fig. 6, where they are identified by the reference characters N, R and L, respectively, these being controlled in the usual manner by a polarized switch control relay 1WR. Relay 1WR is arranged as in the Young application hereinbefore referred to, so as to be normally deenergized, becoming energized either in response to the operation of the route selecting relays for routes over crossover 1 or in response to the operation of the switch lever 1L provided for operating crossover 1 individually. Relay 1WR is held energized by an associated locking relay 1LR as long as the route remains set up, and also until a train which has entered the route has passed over the track switch controlled thereby and has vacated the detector track section.

The switch machines SM control polarized switch indication relays WP as in the above-mentioned Patent No. 1,238,889, and each relay WP controls correspondence relays NC and RC, relay NC or RC being energized only when the associated relay WP indicates that the switches are locked in their normal or reverse position, respectively, to correspond with the last operated position of the control relay WR. Relays WP and WR also control switch indication relays NWK and RWK which are repeaters of relays NC and

RC, but are normally deenergized, one or the other being energized only when the associated switch control relay WR is picked up.

It is to be understood that the control and indication circuits for the remaining switches are similar to those shown in detail for switches 1A and 1B, except that in case of the single switch 3 only one switch machine is required.

Referring now to the route selecting apparatus 10 of Figs. 1A to 1C, a push button P is provided for each signal location or route end, and the track switches may be operated as required to establish any route by momentarily operating the two push buttons identified with the opposite ends of the route, as in the Pelikan Patent No. 2,244,401, granted June 3, 1941, for Railway traffic controlling apparatus, and likewise, as in that patent, the relative order of operation of the two buttons determines the traffic direction, the button operated first functioning as an entrance button, the signal at the corresponding entrance end of the selected route clearing automatically as soon as the route becomes established. The relays involved include an entrance stick relay 25 PS for each button which is picked up in response to the momentary operation of the associated button provided the entrance relays for conflicting or opposing routes are in their released positions and also include one normal and one reverse route relay for each track switch, such as the relays 1ANE and 1RE for switch 1A, or the relays 1BNW and 1RW for switch 1B. The arrangement differs from those employed heretofore in systems of this character in that a pair of route 30 relays is provided for each switch, regardless of whether it is operated singly, like switch 3, or is included in a crossover, like switches 1A and 1B.

The route relays are controlled by the entrance 35 relays and route buttons over a novel circuit network of interconnected circuits arranged like the tracks of the layout to include a two-wire route circuit for each route. Each route circuit constitutes a "loop" extending from a connection to the supply terminal B of a local source of current 40 at a front contact of the entrance relay for the selected entrance end of the route to a point corresponding to the exit end and thence back to the entrance end, over which the route relays (one for each switch of the route) are energized in parallel, the relays E being energized over the upper wire, and the relays W over the lower wire of the two-wire circuit. The circuits associated with the route button 8P for the intermediate signal 45 8 are somewhat differently arranged and include interlocked directional relays for sectionalizing the circuits at that point, these including the exit relays 8XR and 8XS, used only in setting up routes governing traffic from left to right, and the relay 5ANW, used only in setting up routes from right to left. A relay 8PR is also provided which serves in place of button 8P to effect "through routing."

The route circuits are selected in part by the 50 operation of the route relays, and the novel mode of operation may be more readily understood by considering the effect of operating a particular button, such as button 4P, but without tracing the circuits in detail. If this is the first button operated, relay 4PS will pick up, marking point 4 as the entrance point, and energizing a portion of the route circuit for route 4-8 to pick up the route relays 1RE, 8XR and 5ANE, also energizing a portion of the route circuit for route 4-12 to pick up relays 3NE and 7BNE. The points 8 and 55 12 are thereby rendered available as alternative

exists to be selected by the operation of button 8P or 12P, this being indicated by the lighting of the corresponding exit lamps on the track diagram. The energized route relays isolate these route circuits from those for routes having different entrance points such as 2 or 6, and also render the entrance relays controlled by buttons 8P, 10P and 12P non-responsive. If the operation of button 12P follows that of button 4P, for example, it serves merely to connect the two wires of the circuit for route 4-12 together at their exit end to pick up the remaining route relays 5BNW and 1BNW for that route, a front contact of relay 5BNW maintaining the connection after button 12P is released, these relays also isolate the circuit for route 4-12 from those having different exit points, thereby releasing the relays for route 4-8. The route relays, energized in parallel over a front contact of the entrance relay 4PS, then include one for each switch of route 4-12, and relay 4PS is held energized in turn over a front contact of the track relay for the first track section A1T of the route until a train enters the route, or until button 4P is "pulled" to cancel the route manually.

The energized route relays effect the establishment of the selected route by governing the switch control relays WR of Fig. 6 in a novel manner, each switch being operated as soon as the required position is ascertained. For example, button 2P governs routes over crossover 1 normal only, and therefore the required position is known as soon as the entrance button 2P is operated. Accordingly, the circuits of Fig. 6 are so arranged that the switch control relay 1WR is energized normal by relay 1ANE which picks up in response to the operation of the entrance button 2P, but when button 4P is operated, the required position of crossover 1 is indeterminate and the energization of relay 1WR is not effected until the selected exit button 8P or 12P is operated. In this manner the number of switches to be operated simultaneously is reduced, decreasing the maximum demand upon the power source and speeding up operation.

When each track switch assumes the required position, the corresponding indication relay NWK or RWK becomes energized, as already mentioned, and these relays also serve to isolate the energized route circuit from those for conflicting routes, being effective after a train has entered the route and the route relays consequently are released, to restore the route circuits to normal, section by section, as the successive sections are vacated by the train.

The indication relays NWK and RWK also serve to complete a circuit for the control relay HR for the signal at the entrance end of the route, as soon as it is fully established.

The circuits for the relays HR are shown in Fig. 2. Heretofore it has been the practice to include contacts of the route relays in circuits of this character in order to require the operation of both the entrance and exit buttons to reestablish a route already occupied by a train. This result is attained without the use of additional contacts as required heretofore, by energizing the circuits of Fig. 2 over terminals 13 to 18, inclusive, which extend to correspondingly numbered terminals of the route circuits of Figs. 1A to 1C, so that in each case a connection to terminal B for energizing the required relay HR is available only when the corresponding route circuit is energized and

at least one route relay controlled by the exit button has been picked up.

Each signal control relay HR, together with the correspondence relays NC and RC of Fig. 6, prepares a circuit for clearing the corresponding signal, as shown in Fig. 7, but the clearing of the signal is made dependent upon the locking electrically of each switch of the route in the required position in response to the operation of relay HR. The signals, as shown herein, are to be understood to be of the well-known searchlight type, each having a mechanism G, such as that of the E. J. Blake Reissue Patent No. 14,940 of August 31, 1920. The mechanisms G for each interlocked signal, shown in Fig. 7, controls the usual back-lock indication relay RGP as shown in Fig. 4 or 5, which is energized when the signal indicates stop. The mechanisms for the distant signals 21 and 22 control the indication relays 21 RHGP and 22 RGP which are energized when the respective signals indicate either stop or caution.

An approach locking relay AS is provided for each signal, which is normally energized by the associated indication relay RGP when the signal is at stop and is released upon the energization of the associated relay HR prior to the clearing of the signal. Two types of approach locking relay circuit are provided; Fig. 4 shows circuits typical of those used with slow speed signals such as signals 2, 6, 8 and 12, and provide for the energization of relay AS at the end of a relatively short time interval after the signal is manually put to stop, measured by the heating period of the thermal relay TE. Fig. 5 shows circuits used with the high speed signals 4 and 10 where a longer time interval is required, in which case relay TE picks up an auxiliary stick relay TES at the end of its heating period, and relay AS picks up at the end of the subsequent cooling period. These circuits are arranged as in the Vantassel Patent No. 2,198,712, issued April 30, 1940, so as to insure that relay TE is in its normal condition at the beginning of the measured time interval.

It is also to be noted that the circuits of Fig. 5 are so arranged that the approach locking relay is held energized when the home signals which control it are at stop, regardless of the condition of the distant signal, but can be picked up only when the distant signal displays a restrictive indication. This arrangement is claimed in a pending application for Letters Patent of the United States, Serial No. 417,892, filed November 5, 1941 by R. A. McCann, for Railway traffic controlling apparatus.

Each approach locking relay AS functions in such a manner that it must be released to permit the clearing of the associated signal and must be picked up to permit the operation of any switch in a route which such signal governs. Each relay AS, when released, connects the associated signal mechanism to the signal network circuit of Fig. 7 and also releases a series of section locking relays ES or WS, shown in Fig. 4, including one for each track section of the selected route, in accordance with the usual practice, and the section locking relays then release the switch locking relays LR of Fig. 6. The relays LR upon releasing, complete holding circuits for the associated switch control relays WR to lock the switches of the route in the required positions, and by closing their back contacts in Fig. 7, complete the circuit for the mechanism

G for the signal at the entrance to the route to cause it to indicate clear.

It will be seen that the apparatus employed in the system of my invention consists largely of relays; these are arranged in two groups. One group includes the relays of Figs. 2 to 5, all the relays of Fig. 6 except the relays NWK and RWK, and also includes the call-on stick relays 4COS and 10COS, the track relays TR and TP, and the approach relays AR of Figs. 1A and 1C, all of which are to be understood to be of the standard type generally employed in railway signaling. The second group comprises those relays associated directly with the operator's control panel which are preferably of a smaller type, such as that shown in my Patent No. 1,815,947, granted July 28, 1931, for Electrical relays, and are mounted in a cabinet adjacent the control panel of Fig. 10. The relays of this second group include the entrance and route relays of Figs. 1A to 1C, the indication relays NWK and RWK of Fig. 6, already referred to, and in addition include the section indication relays SP of Fig. 8, which as shown in Fig. 11, control the circuits for the white lamps of the track diagram.

It will be readily apparent that the control panel employed with the system of my invention may be of the type shown in my prior application employing a track diagram with linear light units with the route buttons located at the ends of the routes on the track diagram, but an alternative arrangement such as is shown herein in Fig. 10 is preferred, as it provides a more compact arrangement and permits a simplification of the lamp circuits. In Fig. 10 the illuminated indicators K are of relatively small dimensions and are preferably of the telephone lamp type such as is shown in my Patent No. 1,897,668, issued February 14, 1933, for Lamp receptacles. The route buttons P, and likewise the levers L for operating the switches individually, are shown mounted in a row below the diagram. The latter may be of the miniature type such as shown in my Patent No. 1,887,273, issued November 8, 1932, for Circuit controllers.

The lamps of the track diagram are controlled in part by the relays of each of the two groups above mentioned, the circuits therefor being shown in Figs. 9 and 11. For each interlocked signal an indicator GK is provided on the track diagram, comprising normally dark red and green lamps, as shown in Fig. 9. The red signal indication lamp becomes lighted in response to the operation of the associated entrance relay when a route is to be set up, and this lamp is extinguished and the corresponding green lamp is lighted when the signal clears in response to the release of the corresponding indication relay RGP by the signal mechanism, as shown in Fig. 4 or 5. In the case of signal 4A or 10A, the signal will of course remain at stop if a controlling track section in advance is occupied. In this case the operator may reoperate the entrance button to pick up relay 4COS or 10COS, interposing a contact of an interrupter relay CT (Fig. 11) in the lamp circuit to cause the indicator to display a flashing red indication, which changes to a flashing green indication upon the clearing of signal 4C or 10C.

The distant signals 21 and 22 are each provided with an indicator DK comprising a green lamp which is normally dark but which is controlled by the associated relay RHGP of Fig. 5 so as to become lighted when the signal indicates proceed.

The tracks of the diagram include a red lamp

TK for each detector section and an approach lamp AK for each approach section lighted by the release of the track repeater relays TP and approach relays AR of Figs. 1A to 1C so as to indicate the occupancy of the corresponding sections, and also include a plurality of white lamps controlled over front contacts of the track repeating relays TP which are lighted in different combinations to indicate the routes established in response to the operation of the route relays. These include an exit indicator, such as 8K or 12K, for each exit point, a normal and a reverse indication lamp such as 3NK or 3RK for each single switch, two normal and one reverse indication lamps such as 1ANK, 1BNK and 1RK for each crossover, together with one or more additional lamps such as 3K optionally included between the indication lamps for widely spaced switches to enable a row of lights to be more readily traced. The operation is such that when an entrance button is operated, the resulting operation of the route relays causes an exit lamp to be lighted to mark each available exit, lamps 8K and 12K for example, in case button 4 is operated. All of these except the one for the exit end of the selected route become extinguished when the exit button is operated and the exit lamp for the opposite end of that route then becomes lighted. One switch indication lamp for each switch of the route becomes lighted in response to the operation of the relay NWK or RWK for the switch as soon as the switch assumes the required position. Finally, a relay SP of Fig. 8 for each section of the route is picked up in response to the release of the section locking relays of Fig. 3, and these serve to maintain the lighting of the white lamps for each section of the route until the train enters such section even though the route selector relays are released. The control of the white lamps by relays SP serves further to provide an indication of the release of the approach locking effective when a route is cancelled manually.

The white lamps RK not only indicate that the switches are locked reverse when steadily lighted, but they are also controlled over back contacts of the switch indication relays WP and a contact of an interrupter relay CT so as to display a flashing indication in case a switch becomes unlocked or displaced from its last operated position at any time, or if during operation it remains in transit from one operating position to another for a sufficient time for the indication to be observed.

I shall now describe the operation of the apparatus of my invention under different assumed conditions, tracing the circuits in detail. I shall first assume that the apparatus is in the normal condition as shown in the drawing and that the operator desires to clear signal 4A to pass an approaching train over route 4-12.

When the train enters the first approach section 19T, Fig. 1A, the track relay 19TR drops and releases the approach relay 4AR, whereupon the approach indicator 4AK becomes lighted on the track diagram to inform the operator of the approach of the train.

Normally all of the indication lamps shown in Fig. 10 are dark, and each route button is conditioned to function as an entrance button, as already mentioned.

To set up route 4-12, the operator will first operate button 4P momentarily to pick up relay 4PS. The pick-up circuit for relay 4PS may be traced from terminal B at front contact 25 of

track relay A¹TR, Fig. 1A, contact 26 of button 4P, back contacts 75 and 76 of relays 1RW and 1BNW through relay 4PS to terminal C. Relay 4PS picks up and completes its stick circuit which is a branch of the circuit just traced including the normally closed "pull" contact 27 of button 4P and front contact 28 of relay 4PS.

Contact 29 of relay 4PS in Fig. 9 completes the circuit for the red lamp of the signal indicator 4GK on the track diagram, and contact 30 of relay 4PS in Fig. 1A connects terminal B to the upper wire of the two-wire route circuit for each route originating at the location of signal 4.

It will be seen that the track layout provides two alternative routes 4—10, one via 1 reversed and the other via 5 reversed. The former is taken as the preferred route 4—10 in order to free the parallel route 6—12, and the circuits are so arranged that the secondary route 4—10 via 5 reversed is normally unavailable. Furthermore, the preferred route 4—10 via 1 reversed includes the intermediate signal 8 and therefore constitutes a "through route" comprising two routes 4—8 and 8—10 in end-to-end relation, and although my apparatus is adapted to provide "through routing" for the establishment of such routes by the operation of the two end buttons only, it is considered preferable not to employ that method for setting up routes for train movements against the normal direction of traffic, that is, toward a high signal such as 10, and for this reason, through routing is provided for route 2—12 only, and is not provided for route 2—10 nor for route 4—10 via 1 reversed. The track plan shows three routes 4—12, the main line route via 1 normal and 7 normal, and the two "run-around" routes via 1 reversed and 7 reversed, and via 5 reversed and 7 reversed. The main line route 4—12 is of course the preferred route and is the only one of the three provided for in the circuits. Route 4—12 via 1 reversed and 7 reversed, however, can be established by setting up the partial routes 4—8 and 8—12 successively. There are, therefore, normally but two available routes originating at point 4; route 4—8, and the main line route 4—12. The route circuit for route 4—8 extends from terminal B at contact 30 of relay 4PS over a back contact of relay 1BNW from which point one branch extends over back contacts of relays 1NWK and 1ANE through relay 1RE to terminal C. Relay 1RE picks up and extends the route circuit over its front contact 31, wire 32, back contacts 33 and 34 of relays 5ANW and 8XS through relay 8XR to terminal C. Relay 8XR picks up and by closing its contact 35, Fig. 11, lights the exit indicator 8K and also energizes relay 5ANE over a branch of the circuit for relay 8PS extending from terminal B at contact 36 of relay 5TR, Fig. 1C, wire 37, back contacts of relays 5RWK, 5ANW, 5RW and 1SP, front contact 38 of relay 8XR, back contact 39 of relay 8PS through relay 5ANE to terminal C. Relay 5ANE picks up and by opening its back contacts in the circuits for relays 5RE and 5RW prevents button 10P from functioning as an exit button to complete the route circuit for the secondary route 4—10 via 5 reversed. Relay 5ANE also opens its back contact 104 in the circuit for relay 10PS to prevent button 10P from functioning as an entrance button.

The route circuit for the main line route 4—12 extends from terminal B at front contact 30 of relay 4PS over a back contact of relay 1RW from which point a branch extends over back contacts of relays 1RWK, 3RWK and 3RE through relay

3NE to terminal C. Relay 3NE thus picks up in response to the operation of relay 4PS and extends the circuit for route 4—12 over its front contact 40, wire 41, back contacts of relays 5RW and 5RWK, wire 42, back contacts of relays 7RWK and 7RE through relay 7BNE to terminal C. Relay 3NE also opens back contacts in the circuits for routes 6—10 and 6—12, thereby rendering button 6P ineffective. Relay 7BNE picks up and extends the circuit for route 4—12 from wire 41 and the back contact of relay 5RW over wire 43, front contact 44 of relay 7BNE, back contact 45 of relay 12PS to contact 46 of button 12P. Relay 7BNE opens its back contact 47 in the pick-up circuit for relay 12PS, thereby conditioning button 12P to function only as an exit button, and closes contact 48, Fig. 11, to light the corresponding exit indicator 12K on the track diagram.

The operator now presses button 12P, extending the circuit for route 4—12 over contact 46 of button 12P, back contacts 49, 50 and 51 of relays 12PS, 7RE and 7RWK, wire 52, back contacts of relays 5RWK and 5RW through relay 5BNW to terminal C. Relay 5BNW picks up, whereupon button 12P may be released, the energized portion 20 of the circuit for route 4—12 now extending from back contact 45 of relay 12PS over front contact 53 of relay 5BNW, back contacts 49 and 50 of relays 12PS and 7RE, wire 54, front contact 55 of relay 5BNW, wire 56, back contacts of relays 3RE, 3RWK, 1RWK and 1RW through relay 1BNW to terminal C. Relay 5BNW opens its back contacts in the circuits for relays 5RE and 5RW, and relay 1BNW picks up, opening its back contacts in the circuits for relays 1RE and 1RW, whereupon relays 1RE, 8XR and 5ANE release extinguishing the exit indicator 8K. Relay 1BNW closes contact 57, Fig. 11, lighting the exit indicator 4K adjacent the entrance end of route 4—12 on the track diagram.

It will be seen that the route relays 1BNW, 3NE, 5BNW and 7BNE, one for each switch of the route, are now energized in parallel over front contact 30 of the entrance relay 4PS, and that back contacts of these route relays isolate the energized route circuit from those for all conflicting routes.

The switch control relays WR of Fig. 6 are energized in the required direction as soon as sufficient route relays have been operated to define the required switch positions, assuming of course that the associated locking relays LR are picked up. It will be noted that all routes terminating at point 12 require crossover 5 to be normal. Accordingly, in Fig. 6 relay 5WR is energized 50 in the normal direction upon the closing of a front contact of relay 5BNW in response to the operation of button 12P either as an entrance or exit button. Buttons 4P and 12P jointly determine the required positions of the remaining switches of the route, and accordingly, relays 1WR, 3WR and 7WR are energized in the normal direction only when two route relays controlled respectively by the entrance and exit buttons are both energized. For example, relays 1WR and 3WR in the case being described are energized over front contacts of relays 1BNW and 3NE in series, and relay 7WR is energized over front contacts of relays 5BNW and 7BNE in series, as shown in Fig. 6.

Each relay WR operates the associated switch or switches to normal, if they happen to be reversed or if the associated indication relay WP is deenergized, by energizing the normal magnets N and the lock magnets L of the associated switch

machines, as explained in the Coleman patents hereinbefore referred to, whereupon each normal correspondence relay NC picks up, energizing the associated normal indication relay NWK. The relays NWK, upon becoming energized, open their back contacts in the route circuits of Figs. 1A to 1C so as to maintain the circuit for route 4-12 isolated from the others after relay 4PS and the route relays for that route are released.

The relays NWK also complete circuits for lighting the normal switch indication lamps on the track diagram, the white lamps 1BNK, 3NK, 5BNK and 7BNK becoming lighted in response to the closing of contacts 58 to 61 of relays 1NWK, 3NWK, 5NWK and 7NWK, respectively, as shown in Fig. 11.

As soon as route 4-12 is fully established so that each relay NWK is energized, the signal control relay 4HR of Fig. 2 becomes energized over a circuit extending from terminal B at front contact 30 of relay 4PS, Fig. 1A, over the upper wire of the route circuit for route 4-12 as already traced, that is, over wires 41 and 43 to contact 53 of relay 5BNW, Fig. 1C, to terminal 18. From terminal 18 the circuit extends in Fig. 2 over a back contact of relay 12PS and over front contacts of each of the relays NWK and of relay 4PS through relay 4HR to terminal C.

Relay 4HR picks up, opening its back contact 62, Fig. 5, to release the associated approach locking relay 4AS, which relay is normally held energized over its stick circuit, like the corresponding relay of the Vantassel patent hereinbefore referred to.

Referring now to the signal circuit network of Fig. 7, it will be seen that the closing of front contacts 63 and 64 of relay 4HR and of back contact 65 of relay 4AS connects the winding of the mechanism 4AG for signal 4A to a signal circuit corresponding to route 4-12 which, as may be traced from the drawing, extends to terminal B at front contact 66 of relay 12AS associated with the opposing signal 12, and to terminal C at contact 64 of relay 4HR, but which is now open at back contacts 126 to 130 of the relays LR. In Fig. 3, relay 4AS opens contact 67, releasing the section locking relay A1ES for the first section A1T of route 4-12, and relay A1ES, in turn, by opening contact 68, releases relay 3ES for section 3T of the route.

In Fig. 8, relay A1ES closes back contact 69, and relay 3ES closes back contacts 70 and 71, thereby causing the section indication relays A1SP, 3SP and 7SP to pick up, and in Fig. 11, front contacts of the SP relays bridge the closed contacts 48, 57, etc., of the route relays to maintain the white lamps lighted to indicate the route after the route relays release. Lamp 3K is also lighted at this time due to the closing of contact 72 of relay 3SP.

In Fig. 6, relay A1ES opens its front contact 73, releasing the switch locking relay 1LR, and relay 3ES opens contacts 124, 125 and 126, thereby releasing relays 3LR, 5LR and 7LR, whereupon each relay WR, as shown in detail for relay 1WR in Fig. 6, is held energized over its stick circuit including the back contacts of the associated relay LR, and each relay WR holds the corresponding relay NWK energized provided the relays WP and NC remain energized, irrespective of the condition of the associated route relays. The release of the relays LR effects the closing of their back contacts 126 to 130 in the signal circuit of Fig. 7 above mentioned, thereby effecting the energization of mechanism 4AG.

This circuit, it will be seen, includes front contacts of the track relay for each section between signal 4A and the next signal 23 in advance, and also includes pole changer contacts of a relay 5 23HP controlled by that signal, so that signal 4A will display caution or clear, depending upon the position of signal 23, but only if the intervening block is unoccupied. It will be understood that the operator may set up the route even though it is already occupied, back contact 74 of the track repeater relay A1TP providing a connection to terminal B for energizing relay 4PS when the first section A1T is occupied, the connection being re-established over contact 25 of relay A1TR as soon as this section is vacated.

In the event the route is set up and signal 4A remains at stop, the operator may clear the call-on signal 4C by reoperating the entrance button 4P, as in the system of my prior application, to close the pick-up circuit for the call-on stick relay 4COS. As shown in Fig. 1A, this circuit extends from terminal B at contact 25 of relay A1TR or contact 74 of relay A1TP over contact 26 of button 4P, back contact 75 of relay 1RW, front contacts 76 and 77 of relays 1BNW and 4RGP, the winding of relay 4COS, front contact 78 of relay 4HR to terminal C.

Relay 4COS picks up and completes its stick circuit at contact 79, and in Fig. 7 relay 4COS completes the energizing circuit for the call-on signal mechanism 4CG at its front contact 80.

The operation of the main signal mechanism 4AG to the caution or clear position opens its indication contact Y or G, in Fig. 5. The mechanism 4CG, although of similar construction, is arranged to be energized only in the caution direction to open its contact Y, but in either case, when mechanism 4AG or 4CG is energized the opening of one of the contacts mentioned releases the associated back-lock relay 4RGP, and this relay in turn opens contact 81 in the circuit for relay 4AS, thereby insuring that relay 4AS will remain released until conditions are again proper for the operation of the track switches in the route controlled by the signal and the signal has again assumed its stop position.

In Fig. 9, the dropping of contact 82 of relay 4RGP extinguishes the red lamp and lights the green lamp of the signal indication 4GK on the track diagram of Fig. 10. With relay 4COS released, as is the case when the main signal is energized, the green lamp is lighted steadily, but with relay 4COS picked up, a flashing green or red indication is displayed due to the operation of contact 83 of a continuously operating interrupter relay CT shown in Fig. 11.

I shall next assume that the approaching train passes signal 4A or 4C and enters section A1T. If this section is not already occupied by a preceding train, relay A1TR will release and the opening of its contact 25 will release relay 4PS. However, if relay A1TR is already released and relay 4PS is held energized over back contact 74 of relay A1TP, it may be released manually by pulling button 4P momentarily to open contact 21.

Relay 4PS upon releasing releases the energized route relays and also relay 4HR, but without sparking at any contact due to the paths provided for the inductive discharge of the relays through suitable rectifiers as shown. Signal 4A or 4C will be restored to stop allowing relay 4RGP to pick up thereby restoring indicator 4GK to its normal dark position. If the distant signal 21 is properly in its stop or caution position, its contact G will be closed and relay 21RHGP will be ener-

gized allowing relay 4AS to pick up over a back contact of the track relay A1TR shown in Fig. 5. The slow acting track repeater relay A1TP will become deenergized and after a brief time interval will drop its contact 84, in Fig. 11, extinguishing the white lamps 4K and 1BNK and lighting the red lamp A1TK on the track diagram to indicate the occupancy of the first section of route 4-12. Similarly, the release of relays 3TP and 7TP as the train enters the succeeding sections extinguishes the white lamps and lights the red lamps for these sections to register the progress of the train through the route.

When section A1T is vacated relay A1TR picks up reenergizing relay A1ES in Fig. 3, and relay A1ES reenergizes relay 1LR in Fig. 6, thereby releasing relays 1WR and 1NWK in turn. Relay A1ES also releases relay A1SP, in Fig. 8, while relay A1TR reenergizes the slow pick-up relay A1TP which relay is timed to pick up shortly after relay 1NWK releases, so that when relay A1TP picks up the red lamp A1TK is extinguished but without completing the circuit for any of the white lamps.

It will be seen, therefore, that the locking of crossover 1 is released so that a conflicting route such as route 4-8 involving only section A1T of route 4-12 may be set up as soon as that section is vacated. Similar considerations apply to the remaining sections of the route, the apparatus associated with each of these sections being restored to normal by the passage of the train in a similar manner.

It will next be assumed that the apparatus is in its normal condition and that buttons 4P and 8P are operated to set up route 4-8. The operation of button 4P picks up relays 4PS, 1RE, 8XR and 5ANE, and relay 5ANE opens its back contacts in the route circuit for the secondary route 4-10 via 5 reversed as already described. Button 8P is conditioned as an exit button by the opening of back contact 85 of relay 8XR and the closing of contact 86 when button 8P is operated picks up relay 8XS, which then establishes a stick circuit at its front contact 34, at the same time opening the pick-up circuit for relay 8XR, the latter relay being held energized over a stick circuit including contact 87 of button 8P until the button is released. Relay 8XS closes contact 88 thereby extending the route circuit for route 4-8 over back contact 89 of relay 5ANW, wire 98, back contact 91 of relay 1ANE, front contact 92 of relay 1RE, back contact 120 of relay 1BNW and the lower back contact of relay 1NWK through relay 1RW to terminal C. Relay 1RW picks up and opens its back contacts in the route circuit for route 4-12, releasing relays 3NE and 1BNE, and in Fig. 6 relay 1RW completes a circuit over a front contact of relay 1RE to energize relay 1WR in the reverse direction. The crossover 1 is thereby operated to reverse whereupon relays 1WP, 1RC and 1RWK pick up, and relay 4HR becomes energized over the connection to terminal 16. The remaining operations being similar to those already described in connection with route 4-12, further discussion appears unnecessary.

Considering next the routes 2-8, 8-10 and 8-12, it will be apparent that if button 2P is operated as an entrance button, relay 2PS will be picked up over the circuit extending over wire 93 to terminal B at contact 94 of relay 1TR, and then relays 1ANE, 8XR and 5ANE pick up successively. Relay 1ANE completes the normal circuit for relay 1WR in Fig. 6, so that crossover 1 is operated at once. With relay 8XR picked up,

button 8P is conditioned as an exit button, as already described, but there is now another available exit at point 12. Relays 2PS, 8XR and 5ANE being energized, a branch of the circuit for route 8-12 is closed from terminal B at contact 36 of relay 5TR as already traced over wire 37 to front contact 38 of relay 8XR, and thence over back contact 39 of relay 8PS, front contact 95 of relay 5ANE, wire 96, back contact 97 of relay 1ANW, front contact 98 of relay 2PS, back contacts of relays 1NWK and 1BNE through relay 1RE to terminal C. Relay 1RE picks up and extends the circuit from contact 97 over its front contact 99 and back contact 45 of relay 12PS to contact 46 of button 12P. Contact 100 of relay 1RE opens the circuit for relay 12PS, and in Fig. 11 contact 101 of relay 1RE completes the circuit for lighting the exit indicator 12K.

Assuming now that button 8P is operated, relay 8XS picks up extending the circuit for route 2-8 over its contact 88 to terminal 16 to prepare a circuit for the signal control relay 2HR, thereby completing the selection of route 2-8. Relays 8XR, 5ANE and 1RE release in response to the release of button 8P. When relay 8XR is released, button 8P is again conditioned to serve as an entrance button for routes 8-10 and 8-12, and if it is now operated, a circuit is completed from terminal B at contact 36 of relay 5TR over wire 37, back contacts of relays 5RWK and 5ANW, contact 102 of button 8P, back contact 85 of relay 8XR, through relay 8PS to terminal C. Relay 8PS picks up to establish the usual stick circuit and connects terminal B at its front contact 39 to the route circuits for routes 8-10 and 8-12, whereupon relay 5ANE picks up extending the route circuit for route 8-12 over its front contact 95, wire 96 and front contact 103 of relay 8PS to pick up relay 1RE to thereby condition button 12 as an exit button as already described. Similarly, the opening of back contact 104 of relay 5ANE in the circuit for relay 10PS conditions button 10P as an exit button, its lower contact 105 being connected to terminal B over contacts 39 and 95 and wire 106. Relay 1ANW or 1RW may now be picked up by the operation of the exit button 10P or 12P, respectively, to complete the selection of route 8-10 or 8-12, relay 8HR becoming energized over the corresponding route circuit terminal 17 or 18 when the route is established.

Considering next the through route 2-12, it has already been pointed out that when the entrance button 2P is operated, relays 2PS, 1ANE, 8XR, 5ANE and 1RE become energized, connecting terminal B to contact 46 of the exit button 12P. The operation of button 12P will extend the route circuit over back contact 49 of relay 12PS to pick up relay 1RW as for route 8-12, but in the present instance the circuit is further extended over contact 107 of relay 1RW, wire 108, back contacts of relays 5RE, 5RWK and 8PS and front contacts 109 and 110 of relays 8XR and 5ANE, through relay 8PR to terminal C. Relay 8PR picks up and, as will be clear from the drawing, its two lower contacts complete a pick-up circuit for relay 8XS and a stick circuit for relay 8XR the same as when button 8P is operated, but in the present instance relay 8PR prepares a circuit closed when relay 8XS picks up to energize relay 8PS, whereupon relays 8PR and 8XR release due to the opening of the lower back contact of relay 8PS. The relays remaining picked up are relays 2PS, 1ANE

and 8XS for route 2—8, and relays 8PS, 5ANE, 7RE and 7RW for route 8—12, the same as when these routes are set up separately.

A feature of these circuits is that they are so arranged that the through routing is rendered inoperative when there is a train in section 1T approaching signal 8 since under these circumstances it is not desirable to clear signal 8 by the operation of buttons 2P and 12P. This is effected by including a back contact 111 of relay 4SP in the circuit for relay 5ANE in Fig. 1B, and by controlling relay 4SP over a back contact of the track relay 1TR, as shown in Fig. 8.

It is believed that the route circuits for routes 6—10 and 6—12 which have a connection to terminal B at front contact 112 of relay 6PS require no explanation in view of their similarity to those circuits already traced. The circuits for the secondary route 4—10 via 5 reversed may also be readily traced, and it will be seen that when relay 4PS picks up a connection to terminal B at its front contact 30 is extended over contact 40 of relay 3NE and wire 41 and a back contact of relay 5ANE through relay 5RE to terminal C, provided conditions are such that relay 5ANE does not respond to the operation of button 4P as hereinbefore described, but remains released. If relay 5RE picks up, the circuit is extended over its front contact and wire 106 to contact 105 of button 10P, and if button 10P is operated relay 7ANW is picked up to further extend the circuit over its front contacts 113 and 114 and wire 115 to pick up relay 5RW, and from wire 115 over contact 116 of relay 5RW and wire 56 to pick up relay 1BNW. It is clear, therefore, that route 4—10 via 5 reversed will be established in response to the operation of buttons 4P and 10P, provided relay 5ANE is prevented from picking up. This will be the case, for example, if route 2—8 is already set up or if crossover 1 is locked normal by a train in section 1T, in which case relay 1NWK will be picked up to open the circuit for route 4—8, or the secondary route may be selected manually. By reference to Fig. 6 it will be seen that each relay WR will become energized in its normal or reverse direction, provided the associated locking relay LR is picked up, by operating the corresponding individual switch lever such as 1L to the left or right, respectively from the center position shown. That is, crossover 1 may be operated to normal to pick up relay 1NWK, or crossover 5 may be operated to reverse to pick up relay 5RWK by means of the individual levers 1L and 5L, respectively, in which case back contacts of these relays will open the route circuits for the preferred route 4—10 via 1 reversed and thereby permit the selection of the secondary route 4—10 via 5 reversed.

In the foregoing I have considered only the establishment of routes for traffic movements from left to right. For traffic movements in the opposite direction the operations are generally similar except that the lower wire of the route circuit is the one that is energized first and for the intermediate signal location relay 5ANW is operated in place of relays 8XR, 8XS and 8PS. Considering route 10—2, for example, relay 10PS picks up in response to the operation of button 10P as an entrance button, closing a connection to terminal B at its front contact 117 to pick up relays 7ANW and 5ANW to extend the circuit for route 10—2 to contact 118 of button 2P, the closing of contact 118 completing the selection of route 10—2 by the energization of relays 1ANE and 5ANE, relay 10HR being energized over the

connection to terminal 13. Similarly, for the main line route 12—4, if relay 12PS is picked up by operating button 12P a connection to terminal B at front contact 49 of relay 12PS provides for the energization of relays 5BNW and 1BNW, whereupon button 4P may be operated to pick up relays 3NE and 1BNW, relay 12HR being energized over the connection to terminal 14.

The circuits for relay 1RW in Fig. 1A illustrate the principle of selection employed when there are two alternative routes such as the routes 10—4 via 1 reversed and 10—4 via 5 reversed. If relay 10PS is picked up to connect terminal B at contact 117 to the route circuits for both of these routes, relay 1RW, associated with the circuit for the preferred route 10—4 via 1 reversed, will be picked up over front contact 119 of relay 7ANW to open the circuit for relay 1BNW which otherwise would become energized over the circuit for the secondary route 10—4 via 5 reversed. Relay 1RE will then pick up in response to the operation of the exit button 4P to effect the selection of the preferred route. If, however, for any reason relay 1BNW picks up in place of relay 1RW, the operation of the exit button 4P will cause relay 3NE to pick up to effect the selection of the secondary route. The back contacts 120 and 121 of relays 1BNW and 3NE in parallel in the circuit for relay 1RW are both open when the secondary route 10—4 via 5 reversed has been fully selected and prevent relay 1RW from becoming energized to interfere with the circuits for that route. It will be seen that relay 1RW may be picked up not only when point 10 is the entrance point and relay 7ANW is picked up, as above described, but also when point 4 is the entrance point and relay 1RE is picked up first to close its contact 92 as required for setting up route 4—8, and in addition, if the reverse indication relays 1RWK and 1RWK are both picked up to close their contacts 122 and 123. The last-mentioned branch circuit provides a means for manually establishing the run-around route 12—4.

To set up this run-around route 12—4 via 1 reversed and 1 reversed, the operator first moves levers 7L and 1L of Fig. 6 to their right-hand positions, whereby crossovers 7 and 1 are reversed individually and their indication relays 1RWK and 1RWK picked up. The route buttons 12P and 4P are then operated in that order. The open back contacts of the relays 1RWK and 1RWK in the route circuit for the main line route 12—4 prevent the completion of that circuit, while their front contacts 122 and 123 now closed permit relay 1RW to pick up to complete the route circuit for the run-around route.

By reference to Fig. 1C it will be seen that the route circuit in question can be completed only if the lower wire is energized first for the reason that the only available circuit for energizing relay 7RE in response to an operation of button 4P is the one including a front contact of relay 1RW.

In other words, this run-around route circuit is directional and cannot be set up by operating the route buttons 12P and 4P in the reverse order.

The individual switch levers as shown in Fig. 6 are arranged so that they are ineffective unless they are operated at a time when the track switches they control are free to respond. This is accomplished as in the Young Patent No. 2,179,462, issued November 7, 1939, for Railway traffic controlling apparatus, by the provision of

a center contact on each lever which, as will be clear from the drawing, must be closed in order to pick up the associated locking relay LR.

Considering next the secondary route 10-4 via 5 reversed, it will be seen that this route, like the corresponding one for the opposite direction, may be selected in place of the preferred route 10-4 via 1 reversed, by individual switch lever operation, either by operating cross-over 1 normal to pick up relay 1NWK or by operating cross-over 5 to reverse to pick up relay 5RWK. Furthermore, since these indication relays are controlled by the locking relays and hence by the track relays, this secondary route will be selected automatically in response to the operation of buttons 10P and 4P in case, for example, route 2-8 is occupied or if crossover 5 is reversed and section 5T is occupied.

In the foregoing I have described a novel system of route selection involving a route button and associated stick relay for each route end and a single route circuit for each available route extending between the two ends of the track layout over branches of which a route relay for each switch of the route may be energized to thereby establish the route regardless of the order of operation of two route buttons identifying its opposite ends, and in which a signal control relay is energized over another branch of the same route circuit to automatically clear the signal governing traffic movements over the route thus established in one direction or the other, dependent only upon the relative order of operation of the route buttons. I have also pointed out a number of ways in which this arrangement may be varied to suit particular requirements. For example, I have shown how a route may be rendered available only when the route buttons are operated in a particular order, or by positioning one or more of the track switches by individual lever operation prior to the operation of the route buttons, or in the event a preferred alternative route is unavailable. In addition, I have shown how partial routes involving an intermediate signal may be provided for either with or without the operation of an intermediate route button.

Although a relatively simple track layout has been used to illustrate my invention, it is believed that in view of the description of the circuits and operation as presented herein that my invention may be readily applied by one skilled in the art to larger and more complicated track layouts such as are often encountered in practice even though they may differ widely from the layout shown herein.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In an interlocking control system, a track layout including track switches adapted to form different traffic routes, a route button for each route end, a normal and a reverse route relay for each track switch, a route circuit network of conductor portions arranged to provide energizing circuits for the route relays and to be connected end to end over front contacts of such route relays to form route circuits, there being one such circuit for each available route through the track layout, each route circuit comprising

two conductors extending from contacts associated with the route button for one end to contacts associated with the route button for the other end of the corresponding route so arranged that the route relays for the switches of any route which face in opposite directions are energized over different conductors, means normally responsive to the momentary operation of the route button for the entrance end of a desired route to connect a source of current to one conductor of the route circuit for such route at that end thereby successively energizing one route relay for each trailed switch in such route, means for maintaining said source of current connected to said one conductor until the route is cancelled, means responsive to the subsequent momentary operation of the route button for the exit end of the desired route to extend the connection of said source of current to the other conductor of the same route circuit at that end thereby successively energizing one route relay for each facing switch of said route, means controlled by one of the route relays energized over said other conductor for maintaining the connection between the two conductors of the energized route circuit until said route is cancelled, and means controlled by the energized route relays for operating the track switches to corresponding normal or reverse positions as required for the desired route.

2. In an interlocking control system, a track layout including track switches adapted to form different traffic routes, a route button having two normally open contacts for each route end, an entrance relay for each route button, a normal and a reverse route relay for each track switch, a route circuit network of conductor portions arranged to provide energizing circuits for the route relays and to be connected end to end over front contacts of such route relays to form route circuits, there being one such circuit for each available route through the track layout, each route circuit comprising two conductors over which the route relays for switches facing in opposite directions may be separately energized, each conductor being connected at each end over back contacts of the entrance relay for the corresponding route end to one normally open contact of the associated route button, means normally effective to energize each entrance relay in response to the operation of the associated route button comprising a circuit including the other normally open contact of said button to thereby disconnect the two conductors of the adjacent route circuit end from said one contact of the operated route button, means comprising a front contact of the energized entrance relay for supplying current to one conductor only of the route circuit connected thereto to successively energize one route relay for each trailed switch of the desired route, thereby extending the connection of said source of current to the one contact of the route button for the exit end of such route, means including a back contact of one of the energized route relays for preventing the energization of the entrance relay associated with the route button for the exit end of the desired route thereby rendering the operation of such button effective to extend the connection of said source of current to the other conductor of the adjacent route circuit end to successively energize one route relay for each facing switch of the desired route, means including back contacts of the energized route relays for isolating the conductors over which they are controlled for those of conflicting route cir-

cuits, and circuits including front contacts of the energized route relays for operating the track switches to corresponding normal or reverse positions as required for the desired route.

3. In an interlocking control system, a track layout including track switches adapted to form different traffic routes, a route button having two normally open contacts and a normally closed contact for each route end, an entrance stick relay for each entrance button, a normal and a reverse route relay for each track switch, a route circuit network of conductor portions arranged to provide energizing circuits for the route relays and to be connected end to end over front contacts of such route relays to form route circuits, there being one such circuit for each available route through the track layout, each route circuit comprising two conductors extending at each end over back contacts of the entrance relay for the corresponding route end to one normally open contact of the associated route button, the route relays for the switches of any route which face in opposite directions being energized over different conductors, a circuit closed in response to the operation of the route button for the entrance end of a desired route if such route is available, including its other normally open contact for picking up the associated entrance stick relay to thereby disconnect the two conductors of the adjacent route circuit end from said one contact of the operated route button, a stick circuit for each entrance stick relay including its own front contact and the normally closed contact of the associated route button, means including a front contact of the energized entrance stick relay for connecting a source of current to one conductor only of the route circuit for the desired route to successively energize one route relay for each trailed switch of the desired route, thereby extending the connection of said source of current to the one contact of the route button for the exit end of such route, means including a back contact of one of the energized route relays for preventing the energization of the entrance stick relay associated with the route button for the exit end of the desired route thereby rendering the operation of such button effective to extend the connection of said source of current to the other conductor of the adjacent route circuit end to successively energize one route relay for each facing switch of the desired route, means including a front contact of one of the route relays energized over said other conductor for maintaining the connection between the two conductors, means including back contacts of the energized route relays for isolating the conductors over which they are controlled from those of conflicting route circuits, and circuits including front contacts of the energized route relays for operating the track switches to corresponding normal or reverse positions as required for the desired route.

4. In an interlocking control system, a track layout including track switches adapted to be interconnected to form different traffic routes, signals at the ends of the routes for governing traffic movements through the track layout in opposite directions, a route button for each signal location, a normal and a reverse route relay for each track switch, energizing circuits for the route relays comprising route circuit portions conforming to the track portions which are adapted to be interconnected over front contacts of the route relays to form route circuits over which the route relays for the switches of a route

may be successively energized, there being one route circuit for each available route through the track layout, each route circuit comprising two conductors over which the route relays for the switches trailed for opposite directions of traffic movement may be separately energized, means including back contacts of the route relays for isolating the route circuits over which they are energized from other route circuits, means normally responsive to the momentary operation of the route button for either end of an available route to connect a source of current to a route circuit conductor terminating at that end to effect the energization of a route relay for each switch which may be trailed by a train entering the layout at the corresponding route end, the energized route relays being effective to isolate the route circuits for these routes from those having different entrance ends at the same end of the layout, means responsive to the momentary operation of the route button for either end of an available route when one conductor of a route circuit terminating at the corresponding point is already connected to a source of current at its opposite end to extend said connection to the other conductor of the same route circuit to effect the energization of one route relay for each remaining switch of the desired route, the route relays thereby energized being effective to isolate the route circuit for that route from those having different exit ends, and means controlled by the energized route relays for operating the track switches to normal or reverse positions as required for the desired route and for clearing the signal at one end or the other of such route when such route is established depending upon the relative order of operation of the route buttons for the opposite ends of such route.

5. In an interlocking control system according to claim 4, in which the routes established by the operation of the route relays are available for traffic movements in either direction, means for rendering a particular route establishable for traffic movements in one direction only, comprising a connection over which one route relay for a switch of said particular route is energized when current is supplied to one conductor of the route circuit for said route, which includes one or more normally open contacts in multiple one of which is a front contact of a route relay controlled over the other conductor of the route circuit for said particular route, said one front contact being bridged by another contact if the energization of said one route relay is required in order to establish a different route.

6. An interlocking control system for controlling the operation of power operated track switches adapted to form different traffic routes in two directions through a track layout, comprising manually operable entrance and exit contacts for each route end, an entrance stick relay for each route entrance having a pick-up circuit including the associated entrance contact and a normally closed cancelling contact, a normal and a reverse route relay for each track switch for governing its operation, a route circuit network for the control of said route relays including two directional circuits for each available route for separately energizing the route relays for those switches of the route which are trailed by train movements in opposite directions, the two directional circuits for each route extending in opposite directions from an entrance contact at one end over front contacts of the route relays which such directional circuit controls to an exit

contact at its other end, means comprising back contacts of the route relays for each route for isolating the directional circuits for such route from those for conflicting routes, means responsive to the closing of the entrance contact for the entrance end of an available route for energizing the associated entrance relay, means including a front contact of that entrance relay for supplying current to the entrance end of one directional circuit for such route to thereby energize one route relay for each trailing switch of such route, and to extend the energization of such circuit to its exit end, means responsive to the subsequent closing of the exit contact for the exit end of such route for supplying current from the directional circuit already energized at its exit end to the adjacent entrance end of the other directional circuit for the same route thereby energizing one route relay for each facing switch in such route, and switch control relays controlled directly by the energized route relays for operating the track switches to the positions required for such route.

7. An interlocking control system according to claim 6, in which the pick-up circuit for each entrance relay includes back contacts of one or both route relays for a switch located in the routes having the corresponding entrance end, said route relays having energizing circuits including front contacts of the entrance relays for the opposite end of such routes.

8. An interlocking control system according to claim 6, in which the closing of the exit contact for the end of any route establishes a connection between the two directional circuits for such route over back contacts of the entrance relay for the exit end of such route to energize the route relays in one of said circuits by current supplied to the other directional circuit for the same route over a front contact of the entrance relay at the opposite end of said other directional circuit and in which a front contact of one of the route relays which picks up in response to the closing of said exit contact maintains the connection between the two directional circuits for the same route after said exit contact is opened.

9. An interlocking control system according to claim 6, in which back contacts controlled by that route relay which governs the conflicting position of a track switch located adjacent the entrance end of a route and occupying a trailing position with respect to the corresponding traffic direction are located in the circuit for the corresponding entrance relay instead of in the circuit for the adjacent route relay which such entrance relay controls when energized.

10. An interlocking control system according to claim 6, in which a given route is normally unestablishable, a normally inactive switch lever for a switch in said given route, means for operating said switch individually to normal or reverse in response to the movement of said lever from an inactive position to the corresponding normal or reverse position, a normal and a reverse indication relay for said switch, means for energizing the corresponding normal or reverse indication relay when the switch assumes the position to which it is operated by said lever, and means for rendering said given route establishable in response to the operation of the entrance and exit contacts for its opposite ends, comprising a route circuit corresponding to said route including a front contact of that normal or reverse indication relay which becomes energized when said

switch is individually operated to the position required for the given route.

11. In an interlocking control system, a track layout including track switches adapted to form 5 different traffic routes, a route button for each route end, a normal and a reverse route relay for each track switch for governing its operation to a corresponding position, normally inactive individual switch levers for operating the track 10 switches to normal or reverse, normal and reverse indication relays for the track switches, means for energizing the normal or reverse indication relay for each track switch when it assumes the corresponding normal or reverse position 15 in response to the operation of its individual switch lever, a route circuit network including a route circuit for each available route through the track layout each route circuit controlling that route relay for each switch of the corresponding 20 route which governs the switch to the position required for that route, each route circuit also including a back contact of that indication relay for each switch of the corresponding route which becomes energized when that switch is individually 25 operated to a conflicting position, means responsive to the successive operation of the two route buttons for the opposite ends of any route to supply current to the route circuit for such route to effect the energization of one route relay for each switch of the route but only if the indication relay contacts in such route circuit are closed, and switch control relays controlled directly by the energized route relays for operating the track switches to the positions required for such route.

12. In an interlocking control system, a track layout including track switches adapted to form different traffic routes, a route button for each route end, a normal and a reverse route relay 40 for each track switch, locking relays for the switches each of which is energized only when conditions are proper for operating the corresponding switch circuits including front contacts of the route relays and of the associated locking 45 relays for effecting the operation of the track switches to normal or reverse, normal and reverse indication relays for the track switches, means for energizing the normal or reverse indication relay for each track switch when the corresponding normal or reverse route relay is energized and the switch assumes the position to which it is operated by such route relay, a route circuit network including a route circuit for each 50 available route through the track layout each route circuit controlling one route relay for each switch of the corresponding route for governing the switch to the position required for that route, each route circuit also including a back contact of that indication relay for each switch of the 55 corresponding route which becomes energized when that switch is operated to a conflicting position, means responsive to the successive operation of the two route buttons for the opposite ends of any route to supply current to the route circuit for such route to affect the energization of one route relay for each switch of the route but only if the indication contacts in such route circuit are closed, and means effective if a locking relay becomes released when the normal or 60 reverse indication relay for the corresponding switch is energized to maintain such indication relay energized as long as said locking relay remains released.

13. In an interlocking control system, a track layout including track switches adapted to form

different traffic routes, signals at the ends of the routes for governing traffic movements through the track layout in opposite directions, a route button for each signal location, a normal and a reverse route relay for each track switch for governing its operation, a signal control relay for controlling each signal, a circuit network of interconnected route circuits including a distinctive circuit for each route over which one normal or reverse route relay for each track switch of such route and the signal control relay for the signal at one end or the other of such route all successively energized by current supplied to the circuit at the corresponding end, means responsive to the successive operation of the route buttons for the entrance and exit ends of a desired route to supply current to the corresponding route circuit to successively energize one route relay for each switch of such route and to prepare a circuit for that signal control relay which controls the signal at the entrance end of such route, and means including indication contacts controlled by the track switches for completing said prepared circuit when the switches assume the required positions as determined by the energized route relays to effect the clearing of the signal at the entrance end of the corresponding route.

14. An interlocking control system for selecting different traffic routes through a track layout provided with power operated track switches, comprising polarized switch control relays for operating the switches, an entrance and exit route button for each route end, a normal and a reverse route relay for each track switch having front contacts for controlling the associated polarized relay, means responsive to the successive operation of the route buttons for the entrance and exit ends of any route to successively energize two series of route relays, those energized by the entrance button comprising one for each trailing switch and those energized by the exit button comprising one for each facing switch in such route, and circuits for operating each polarized switch control relay to normal or reverse as required to establish said route including said front contacts of the normal or reverse route relay for the track switch which such polarized relay controls, the circuit controlled by a particular route relay of one series also including a front contact of an energized route relay of the other series which also controls another polarized relay associated with a different track switch in the same route.

15. An interlocking control system according to claim 14, in which the circuit for operating one switch control relay to the required position is controlled by one route relay only and that for operating another to the required position includes in series, a front contact of a route relay for the same track switch and a front contact of a route relay for another track switch facing in the opposite direction in said route.

16. An interlocking control system according to claim 14, in which the circuit for operating a particular switch control relay to one position is controlled by one route relay only and that for operating the same control relay to its other position includes in series, a front contact of the other route relay for the same track switch and a front contact of a route relay for another track switch facing in the opposite direction in the same route.

17. An interlocking control system according to claim 14, in which the circuits for operating

each of the two switch control relays which control adjoining track switches facing in opposite directions in said route to positions to establish such route, include in series, front contacts of the route relays for both switches.

18. In an interlocking control system according to claim 14, in which the polarized control relay for a given track switch is operable to different positions to extend one or the other of two alternative routes having the same entrance end to a common exit end and the two route relays for the given track switch are arranged to be supplied with current from the same source, the circuit for each including a back contact of the other; a circuit for operating the polarized relay to the position required for one alternative route including a front contact of one of said route relays, a circuit for operating the polarized relay to the position required for the other alternative route including front contacts of said other route relay and of a second route relay, said second route relay being one which controls a second track switch in said other alternative route, and means for bridging the back contact in the circuit for said one route relay to render said one alternative route establishable when both are available, comprising a back contact of said second route relay.

19. In an interlocking control system, a track layout including two tracks connected by a pair of track switches to form a crossover route when reversed and parallel routes when normal, a polarized switch control relay for controlling said track switches, a normal and a reverse route relay for each track switch, two normal energizing circuits for said switch control relay, one including a front contact of one normal route relay and the other a front contact of the other normal route relay, a reverse energizing circuit for said switch control relay including in series front contacts of both reverse route relays, means for selectively energizing said route relays to complete a circuit for said switch control relay, and means controlled by said switch control relay when energized for operating both track switches to normal or reverse.

20. In an interlocking control system, a track layout including two tracks connected by a pair of track switches to form a crossover route when reversed and parallel routes when normal, a polarized switch control relay for controlling said track switches, a normal and a reverse switch indication relay, an energizing circuit for each indication relay closed when the polarized relay is energized in the corresponding normal or reverse direction and the track switches are in the corresponding normal or reverse position, a normal and a reverse route relay for each track switch, manually controllable circuits for selectively energizing said route relays the circuit for each normal route relay including back contacts of the reverse route and indication relays and the circuit for each reverse route relay including back contacts of the normal route and indication relays, two circuits for energizing said polarized relay in the normal direction including front contacts of said two normal route relays respectively, and one circuit for energizing said polarized relay in the reverse direction including in series front contacts of said reverse route relays.

21. In an interlocking system for the control of railway signals which govern traffic movements in opposite directions over traffic routes in which there are power operated track switches

facing in opposite directions, a normal and a reverse route relay for each switch, manually operable entrance and exit contacts and an entrance relay for each signal location, circuits for selectively energizing said entrance relays each including the associated entrance contact and a back contact of a route relay for a switch occupying a facing direction for the corresponding traffic direction, a circuit for energizing one route relay for each switch which is in the trailing position for a given traffic direction in a given route including a front contact of the corresponding entrance relay, a pick-up circuit for one route relay for each facing switch in said given route including said entrance relay front contact, a back contact of the entrance relay for the opposite end of the route and the exit contact associated therewith, a holding circuit for one route relay for each facing switch in said given route including front contacts of one of said facing switch route relays and of said entrance relay, means controlled by the energized route relays for operating the track switches of the given route to the positions required for said route and for clearing the signal associated with the energized entrance relay when the switches assume such positions.

22. In an interlocking control system according to claim 21, in which a signal control relay is provided for each signal for governing its operation, and in which the signal control relays are controlled over a route agreement circuit network including a circuit for each route each of which includes the signal control relay for the signal at the entrance end of the route, a front contact of the associated entrance relay, and normally open contacts which close when the track switches of a route which such signal governs assume the positions to which they are controlled by the energized route relays, and means for supplying each such circuit with current over a back contact of the entrance relay for the exit end of the corresponding route, comprising a connection from such back contact to the holding circuit for the facing switch route relays established by the closing of the corresponding exit contact.

23. In an interlocking control system for the control of railway signals governing traffic movements in two directions through a track layout in which power operated track switches provide different traffic routes, route buttons for the ends of the routes, a normal and a reverse route relay for each track switch, an entrance relay for each signal location, a circuit for energizing each entrance relay controllable by the associated route button, route circuits for the different routes each arranged to be supplied with current over a front contact of the entrance relay associated with a route button which is operated to designate the corresponding point as the entrance end of a desired route to energize one route relay for each switch which occupies a trailing position in any route having its entrance end at that point, means comprising back contacts of the route relays thereby energized for rendering the entrance relays for the opposite ends of such routes non-responsive to the operation of their route buttons, means responsive to the operation of a route button for the exit end of a route having those route relays picked up which its entrance relay controls for energizing one route relay for each facing switch of such route over the same route circuit, means including back contacts of the route relays in

that route circuit for isolating it from route circuits for conflicting routes, and means controlled by said energized route relays for operating the track switches as required to establish the corresponding route and to clear the signal associated with the energized entrance relay when the switches assume such position.

24. In an interlocking control system according to claim 23, in which a signal is located at an intermediate point in a given route, a route button and an entrance relay being provided for controlling such signal, and in which the signal at one end of such route governs traffic movements in one direction over a first portion of the given route extending only to said intermediate point, the signal at said intermediate point governs traffic movements in the same direction over a second portion of said route extending to its opposite end, and the signal at said opposite end governs traffic movements in the other direction over the entire route, a directional relay for each direction associated with said intermediate point and controlled over the route circuit for the given route, the energizing circuit for each directional relay including a front contact of the entrance relay for the corresponding end of such route and a back contact of the other directional relay, a circuit for controlling the entrance relay for each end of the given route by the associated route button including a back contact of the opposing directional relay, and a circuit for controlling the entrance relay for the signal at said intermediate point in response to the operation of its route button including back contacts of both directional relays.

25. In an interlocking control system according to claim 23, in which a signal is located at an intermediate point in a given route, a route button and an entrance relay being provided for controlling such signal, and in which the signal at one end of such route governs traffic movements in one direction over a first position of the given route extending only to said intermediate point, the signal at said intermediate point governs traffic in the same direction over a second portion of said route extending to its opposite end, and the signal at said opposite end governs traffic movements in the other direction over the entire route, a directional relay for each direction associated with said intermediate point and controlled over the route circuit for the given route, the energizing circuit for each directional relay including a front contact of the entrance relay for the corresponding end of the route and a back contact of the other directional relay, an exit stick relay for said intermediate point only, a pick-up circuit for said exit stick relay including a first portion of the route circuit for the given route controlled directly by the entrance relay for the first portion of such route and also including a back contact of the opposing directional relay and a normally open contact of said intermediate route button, means controlled by said exit relay when energized for sectionalizing the route circuit at said intermediate point, means for holding said exit stick relay energized over said first route circuit portion, means controlled by said exit stick relay for completing the route circuit for the first portion of the given route to effect the clearing of the signal for governing traffic movements over said first portion of the given route, a circuit for controlling the entrance relay for the signal at said intermediate point in response to the operation of its route button

including back contacts of both directional relays, and means controlled jointly by said exit stick relay and said intermediate route button for releasing the directional relay controlled by the energized entrance relay for the first portion of said given route to render the entrance relay at said intermediate point responsive to a subsequent operation of said intermediate route button.

26. In an interlocking control system, a first signal at one end of a track layout for governing traffic movements over a first portion of a traffic route through said layout, a second signal at an intermediate point in said route for governing traffic movements in the same direction over a second portion of said route, a route button for each end of said route and for said intermediate point, an entrance relay for each signal, each normally responsive to the operation of the associated route button, a route circuit supplied with current over a front contact of the entrance relay for the second signal for clearing that signal in response to the operation of the route button for the exit end of the route, a directional relay having its energizing circuit supplied with current over a front contact of the entrance relay for the first signal, means rendering the route button for said intermediate point ineffective to control the entrance relay for the second signal when said directional relay is energized, an exit relay responsive to the operation of the route button for said intermediate point provided the entrance relay for the first signal is energized, means controlled by said exit relay and the intermediate route button for releasing said directional relay to render the entrance relay for the second signal responsive to a subsequent operation of its route button, a through route relay having an energizing circuit which includes a front contact of said directional relay and a

10 15 20 25 30 35 40

back contact of the entrance relay for the second signal, means comprising the route button for the exit end of the route for completing the circuit for said through route relay provided its operation follows that of the route button for the entrance end of the route, and circuits including front contacts of said through route relay for energizing said exit relay and the entrance relay for said signal for clearing both said first signal and said second signal in response to the operation of the route buttons for the two ends of the route.

27. In combination, a track layout including a plurality of track sections containing track switches for arranging different traffic routes, a route relay for each position of each switch, manually controllable means for selectively energizing said route relays as required to establish the different routes, a miniature track diagram arranged to represent said track layout, a track indication lamp mounted at each junction of two tracks representing a track switch on said diagram, normal and reverse switch indication lamps of a color different from that of said track indication lamp mounted adjacent thereto, one in each of the two tracks on the trailing side of the corresponding track switch on said diagram, a track relay for each track section, a circuit for each normal or reverse indication lamp including a front contact of the track relay for the section in which the corresponding switch is located, a front contact of a route relay energized when a route over the switch in the corresponding position is to be established, and a contact controlled by the track switch which closes when the switch assumes such position, and a circuit for the associated track indication lamp including a back contact of said track relay.

LLOYD V. LEWIS.
